CONTINUE PROCESS APPARATUS

August Hartmann, Berlin-Lichterfelde, Walter Hoefinghoff, Hohenlimburg Obernahmer, and Alex Luchtenberg and Hubert Kempf, Wuppertal-Barmen, Germany, assignors to American Bemberg Corporation, New York, N. Y., a corporation of Delaware

Application January 6, 1933, Serial No. 650,513
In Austria March 5, 1932

3 Claims. (Cl. 18—8)

The invention comprises a process and apparatus for the continuous manufacture of artificial filaments.

It has already been proposed to subject the artificial filament to the precipitation and after treatment while being placed upon endless ribbons or in grooves, in order to be finally dried and wound upon take-up rollers. This process has the disadvantage that it requires much 10 speed; it is, therefore, not applicable if an economical spinning speed is employed.

It has been suggested also that the artificial filament be guided in a helical path over rollers or discs, whereby grooved rollers or guide bars were used in order to maintain the helical path. These processes also require a great deal of skill and, more particularly, considerable time until the necessary number of windings are placed around the treating roller. This disadvantage is 20 not only encountered during the start of the spinning process but also on the occasion of thread breaks. Consequently, the process required a comparatively large number of operators and could, therefore, not gain popularity in the trade.

It must also be considered that at an economical spinning speed, a very large number of windings are required, in order to sufficiently treat the single filament.

Attempts are being made to prevent these difficulties through the use of a reel, whose different segments intermittently rotate in radial direction, in order to obtain an advancing of the filament. However, these devices are expensive and also require the guidance of the filament in numerous 35 windings in order to obtain a sufficient treatment of the thread.

The present invention is based upon the new idea that it is possible to obtain a much better treatment through the employment of two ordinary rotatable rollers, under certain conditions, whereby the filament is automatically advanced.

The freshly spun filament is guided in a helical path over one or more pairs of rollers which rotate in the same direction as the filament advances. The shafts of the rollers are positioned at an angle to each other. The filament is treated during its movement on the rollers. The filament is first of all placed upon the rollers in the form of a closed loop. The loop is suitably formed 50 through a manifold winding of the thread, whereby the different windings touch one another. The windings of the thread adhere to one another due to their moisture.

After several turns of the rollers, it is noticed 55 that the loop of thread slowly travels along the

rollers winding the thread in a helical path. If rollers are employed which are arranged at an angle to one another vertically, the filament always travels towards the geometrical point of intersection of the shaft independent of the direction of rotation of the rollers. If rollers are employed which are arranged at an angle to one another horizontally, the direction of advance of thread depends upon the direction of rotation of the rollers. Although the advance of thread 10 by the employment of the first mentioned rollers takes place while the thread is passing through the air, i. e., between the rollers, it mainly takes place as long as the filament is in contact with the rollers, if the second mentioned type of rollers 15 are employed.

It is important during this movement of the thread that the filament temporarily revolves on the roller due to its advance. By this means the filament is not only brought in contact with the liquid at all points, but also an especially intensive exchange of liquid is effected through the intermittent compression and loosening of the filament, which otherwise is only possible through diffusion.

At an automatic advance of thread on the rollers and a comparative small number of thread windings, the present process makes it possible to obtain a sufficient wet treatment and, particularly, a complete washing process, without any 30 chemical impurities remaining in the filament. By this means it is possible to keep the dimensions of the washing devices within suitable limits in case a high spinning speed is applied.

Moreover, it is possible to provide a series of 35 wet treatments, whereby the filament may also be bleached, dyed or sized, if desired.

Further advantages may be obtained if several filaments from different adjacent spinnerettes are placed together upon one pair of rollers. After 40 several turns of the rollers, the different filaments separate from one another and move in separate helical paths and at a uniform distance from each other, towards the end of the rollers.

The invention also results in a considerable 45 saving of time and an increase of the safety of operation possible, since no special measures are necessary in order to guide the filament in a helical path over the rollers. An entanglement of the different windings is not possible.

The wet treatment of the filament takes place 50 through the rotation of one roller or of both rollers in the necessary baths. It is, however, sufficient if the rollers are sprayed with the liquids. The best results will be obtained if the entire sur- 55
